(57) CLAIM

We claim the ornamental design for a brim and neck shade with straps, as shown and described.

DESCRIPTION

FIG. 1 is a left side top front perspective view of our new design for a brim and neck shade with straps.

FIG. 2 is a left side view thereof.

FIG. 3 is a front view thereof.

FIG. 4 is a rear view thereof.

FIG. 5 is a top view thereof; and,

FIG. 6 is a bottom view thereof.

The broken lines shown in the drawings show unclaimed subject matter only and form no part of the claimed design.
